UNITED STATES PATENT OFFICE.

THOMAS W. BROWN, OF IOWA FALLS, IOWA.

SHOCKER ATTACHMENT FOR BINDERS.

No. 815,141.

Specification of Letters Patent.

Patented March 18, 1906.

Application filed June 1, 1904. Serial No. 210,690.

To all whom it may concern:

Be it known that I, THOMAS W. BROWN, a citizen of the United States, residing at Iowa Falls, in the county of Hardin and State of Iowa, have invented a certain new and useful Shocker Attachment for Binders, of which the following is a specification.

The objects of my invention are to provide a shocker attachment for harvesters of simple, durable, and inexpensive construction which can be easily and readily attached to the harvesters already in use and which is adapted to bind several bundles together and when the bundles are tied together and a shock is formed to allow the shock to be dropped onto the ground-surface in a standing position.

A further object is to provide a shocker in which a certain predetermined number of bundles may be bound together as the harvester is operated and yet to avoid the necessity of binding each separate bundle to the other bundles, and thus lessen the labor in the operation of the bundles when taking the stack down.

A further object is to provide an auxiliary needle attachment for shocking which is mounted on an extension of the shaft upon which the binder-needle is mounted and the ordinary knotter attachments designed to coact with the auxiliary needle in knotting the binding material when a certain predetermined number of bundles have been bound by the binding-needle.

My invention consists in certain details in the construction, arrangement, and combination of the various parts of the device whereby the objects contemplated are attained, as hereinafter more fully set forth, pointed out in my claims, and illustrated in the accompanying drawings, in which—

Figure 1 is a plan view of the delivery side of a binder, showing the ordinary binder attachment and my shocking attachment. Fig. 2 is a sectional view of the delivery side of a binder, showing the way in which the bundles are held together in constructing the shock and my shocker-needle and other attachments. Fig. 3 is a detail view showing in elevation the shocker attachment mounted on the ordinary binder. Fig. 4 is a detail view of the shock-delivery mechanism and the way in which the shocks when bound are stood upon the ground-surface. Fig. 5 is a detail view of the means for directing the in-

clination of the delivery rotation. Fig. 6 is a detail view of the binder-cam.

Referring to the accompanying drawings, I have used the reference-numeral 10 to indicate the platform over which the grain to be bound passes as it is fed to position where it is bound.

The reference - numeral 11 indicates the frame which extends from the body of the harvester underneath the side delivery mechanism. It is upon this frame 11 that the entire binder and shocker attachment is mounted. Mounted on the frame 11 is a substantially U-shaped frame having the circular lower portion 12, the upper portion 13, and the connecting-piece 14 therein. The connecting-piece 14 extends through the platform 10, and the lower portion 12 is mounted beneath the platform 10 and the portion 13 above said platform 10 and outside of the portion 12. Extending longitudinally of the portion 12 beneath and transversely of the platform 10 is the needle-shaft 15, having the crank 16 at its forward end. Keyed to the needle-shaft 15 is the binding-needle 17 and the shocker-needle 18, each of which is made in the ordinary way and is shown fully in Fig. 1 of the drawings. Extending longitudinally of the upper portion 13 of the U-shaped frame is the knotter-shaft 19, having the bevel-gear 20 on its forward end. This bevel-gear is in mesh with the bevel-gear 21, which is operatively connected with the main driving-shaft 22 by means of the shaft 23 and the bevel-gears 24 and 25, so that as the main driving-shaft is operated the bevel-gear 20 will be correspondingly operated. There is a bearing 26 extending forwardly from the bevel-gear 20, and a shaft 27 connects the bearing 26 with the crank 16 on the needle-shaft 15, so that when the shaft 19 is driven, the needle-shaft 15 will be rocked so as to operate the needles mounted thereon and force said needles upwardly and partially around the grain to be bound and into the knotters which are connected with the upper portion 13 of the U-shaped frame.

Connected with the knotter-shaft 19 and adjacent to the free end of the upper portion 13 of the U-shaped frame is the ordinary knotter mechanism of the binder. Rotatably mounted at the rear of the ordinary knotter mechanism on the binder-shaft 19 is the cam-wheel 28, having the gear 29 on a portion of its periphery. The cam 28, with its

gear 29, is designed to operate the knotter and the knife for severing the binding material after it has been knotted. A more complete description of the knotter and the knife for cutting the binding material is deemed unnecessary, owing to the fact that these parts are duplicates of the ordinary binding mechanism. I have provided a notch 30 in the periphery of the gear 29, into which the mechanism for retaining the cam against movement is forced except when it is thrown into operation by releasing said mechanism. Extending rearwardly from the cam 28 is the ratchet-faced projection 31. This ratchet-faced projection encircles the shaft 19.

Slidably mounted on the shaft 19 and at the rear of the ratchet-faced projection 31 is the ratchet-faced collar 32, having the annular groove 33 encircling it. Encircling the rear end of the shaft 19 is the sleeve 34, which is connected with the guard-frame 35 and assists in supporting the free end of said guard-frame. Extending upwardly from the sleeve 34 are the lugs 36. Slidably mounted in these lugs 36 and extending longitudinally above the shaft 19 is the mechanism for throwing the shocker-knotter out of or into operation. This comprises the bar 37, which has the projection 38 extending at right angles to it, upon which the roller 39 is mounted, the purpose of which is hereinafter made clear. This sliding bar has a downwardly-extending member 40, which enters the groove 33 in the collar 32, so that as the sliding member 37 is moved forwardly and rearwardly the ratchet-faced collar will be forced into or out of engagement with the ratchet-faced projection 31. Connected with the forward end of the sliding member 37 is the cam-engaging member 42, having the downwardly-extending projection 43 at its forward end, which is designed to enter the notch 30 in said cam and hold the cam in position against rotary movement when the ratchet-faced collar 32 is out of engagement with the ratchet-faced projection 31. There is a spring 44 mounted on that portion of the sliding member 37 which is between the lugs 36, designed to normally force the sliding member forwardly and so that the ratchet-faced collar 32 will be normally forced forwardly and into engagement with the ratchet-faced projection 31 except when the sliding member is held at its rearward limit of movement against the resistance of the spring 44. Mounted on the extreme rear end of the knotter-shaft 19 is a gear 45, which is in mesh with the gear 46, which is mounted on the stub-shaft 47 at the rear of the binder-shaft. This gear 46 is so mounted that the roller 39 on the sliding member 37 will be normally in engagement with its rear face. On the rear face of the gear 46 is a curved projection 48, against which the roller is designed to rest

during part of the movement of said gear and while the shock is being formed. When the roller is in engagement with the curved projection 48, the sliding bar is thrown to its rearward limit of movement, and the projection 43 is in the notch 30, the ratchet-faced collar 32 is out of engagement with the ratchet-faced projection 31, and the cam 28, which operates the knotter and knife, is maintained in position against rotary movement. As soon as the roller 39 passes out of engagement with the circular projection 48 it drops against the rear face of the gear-wheel 46, and the spring 44 causes the lug 43 to be thrown out of engagement with the cam 28 and the ratchet-faced collar 32 to be forced into engagement with the ratchet-faced projection 31, and as the shaft 19 continues its rotation the knotter and knife will be operated by the cam 28 when the shocker-needle reaches its proper position. As soon as the roller 39 again engages the projection 48 the parts will take the relative positions above described and the cam for operating the shocker-knotter and knife will be maintained out of operation until the next shock is formed. It will be seen that in operation both the binder-needle 17 and the shocker-needle 18 will be rocked at every revolution of the shaft 19 and that if the ordinary binder-knotter is used in connection with the binder-needle 17 the knotter and cutter will operate with each operation of the binder-needle 17, but that although the shocker-needle operates with each rocking of the needle-shaft 18 and revolution of the knotter-shaft 19 the shocker-knotter and cutter will not operate in conjunction with the shocker-needle 18 except when the ratchet-faced collar 32 is in engagement with the ratchet-faced projection 31, and as these parts are in engagement with each other only when the roller 39 is out of engagement with the circular projection 48 the knotter will only operate after a certain number of bundles have been formed and only when a predetermined number of bundles have been bound by the binder-needle. Inasmuch as the twine or other binding material is attached to the binder in the ordinary way a further description of this is deemed unnecessary. Suffice it to say that the twine extends from its point of attachment in the binder through the needles 17 and 18 in the ordinary way and extends to the twine-box 49.

Pivottally mounted at the extreme outer side of the frame 11 is the rock-shaft 50, to which the shock-supporting rods 51 are pivottally attached and capable of movement, as shown in Fig. 5. These supporting-rods 51 are held firmly against rotary movement on the shaft 50, but they are capable of slight pivotal movement, so that their lower ends swing longitudinally of the shaft as the shaft

is rocked. There is a guide-bar 52 through the curved slots 53, in which the shock-supporting rods 51 pass. These slots 53 act as guides for the rods 51 as the rock-shaft 50 is rocked—that is, when the rock-shaft 50 is rocked in one direction the outer ends of the rods 51 will be swung downwardly and rearwardly, and when said shaft 50 is rocked in the opposite direction the rods 51 will be drawn to their upper limit of movement—that is, moved forwardly and upwardly to their supporting position. Firmly attached to the forward end of the rock-shaft 50 is the arm 54, having the operating-rod 55 pivotally attached to it. This rod 55 is held in position by any mechanism suitable to maintain it against longitudinal movement and to release it from its locked position when desired. When the rod 55 is at its inner limit of movement and locked in that position, the shock-supporting rods 51 will be at their upper limit of movement, so that the bundles of grain can be fed down upon them and they will support these bundles. When, however, a shock has been formed and the rod is released and allowed to move to its forward limit of movement, the weight of the shock will cause the supporting-rods 51 to be moved to their rearward lower limit of movement, and thus the shock will be allowed to fall upon the ground and as it falls be so turned that when it reaches the ground it will be in a standing position, said shock being turned by the direction of the rods 51 when they are in their lower rearward limit of movement, together with the assistance of the stationary rod 56, which extends outwardly from and at right angles to the rear end of the plate 52, in such a way that the upper portion of the shock strikes said rod as the lower portion of the shock is allowed to slide off from the supporting-rods 51. This rod 56 is of such length that when the shock is in an upright position on the ground-surface it will simply cause the shock to be moved a slight distance farther away from the binder as the machine advances over the ground-surface by simply rotating it slightly.

In practical operation the bundles are forced one at a time after being bound by the binder against the twine and when the predetermined number of bundles have been moved toward the shock-supporting rods the shocker-knotter is enabled to coöperate with the shocker-needle in securing the binding material around the shock, and then the knotter mechanism is thrown out of operation until a sufficient number of bundles to form a shock have been made, and then the knotter and needle again coöperate to tie the ends of the rope for holding the bundles and the shock together. The operator dumps the shocks from the supporting-bars 51 onto the ground by operating the rod 55 and releasing

the supporting-rods, so that the weight of the shock causes it to move downwardly and on account of its engagement with the rod 55 is forced into a standing position.

Having thus described my invention, what I claim, and desire to secure by Letters Patent of the United States therefor, is—

1. In a device of the class described, a needle-bearing shaft, a shocker-needle mounted on said shaft, a knotter-shaft operatively connected with the needle-shaft, a cam rotatably mounted on the knotter-shaft, a knotter and cutting mechanism designed to be operated by said cam, means for holding the cam against rotary movement on the shaft during a certain number of revolutions of the shaft and for throwing the cam into operative connection with the shaft after a certain number of revolutions of the shaft to operate the knotter and the cutting mechanism and cause the knotter to coact with the shocker-needle.

2. In a device of the class described, a needle-bearing shaft, a shocker-needle mounted on said shaft, a knotter-shaft operatively connected with the needle-shaft, a cam rotatably mounted on the knotter-shaft, a knotter and cutting mechanism designed to be operated by said cam, means for holding the cam against rotary movement on the shaft during a certain number of revolutions of the shaft and for throwing the cam into operative connection with the shaft after a certain number of revolutions of the shaft to operate the knotter and the cutting mechanism and cause the knotter to coact with the shocker-needle, and means for holding the twine used in shocking taut as the needle is operated.

3. In a binder, a needle-bearing shaft, a binder-needle on the shaft a shocker-needle mounted on the shaft, a knotter-shaft operatively connected with the needle-shaft, a cam rotatably mounted on the knotter-shaft, a knotter and cutting mechanism designed to be operated by said cam, means for holding the cam against rotary movement on the shaft during a certain number of revolutions of the shaft and for throwing the cam into operative connection with the shaft after a certain number of revolutions of the shaft to operate the knotter and the cutting mechanism and cause the knotter to coact with the shocker-needle, and means for keeping the twine used in the binding and shocking taut as the needles are operated.

4. In a device of the class described, a needle-bearing shaft, a shocker-needle mounted on said shaft, a knotter-shaft operatively connected with the needle-shaft, a cam rotatably mounted on the knotter-shaft, a knotter and cutting mechanism designed to be operated by said cam, means for holding the cam against rotary movement on the shaft during

a certain number of revolutions of the shaft and for throwing the cam into operative connection with the shaft after a certain number of revolutions of the shaft to operate the knotter and the cutting mechanism and cause the knotter to coact with the shocker-needle, and means for keeping the twine used in shocking taut as the needle is operated.

5. In a device of the class described, a frame, a binder connected with the frame, a shocker, means connected with the shocker for throwing its operative parts out of or into operation as the binder is operated, pivotally-mounted shock-supporting rods mounted on the frame outside of the binder and shocker, and means for locking the shock-supporting rods at their upper limit of movement and for releasing said rods to allow them to swing to their lower limit of movement.

10. 6. In a device of the class described, a frame, a binder connected with the frame, a shocker, means connected with the shocker for throwing its operative parts out of or into operation as the binder is operated, pivotally-mounted shock-supporting rods mounted on the frame outside of the binder and shocker, means for supporting the rods at their upper limit of movement and means for directing the rods as they are swung downwardly and rearwardly by the weight of the shock when these rods are released from their upper limit of movement.

15. 7. In a device of the class described, a frame, a binder connected with the frame, a shocker, means connected with the shocker for throwing its operative parts out of or into operation as the binder is operated, pivotally-mounted shock-supporting rods mounted on the frame outside of the binder and shocker, means for locking the shock-supporting rods at their upper limit of movement and for releasing said rods to allow them to swing to their lower limit of movement, and means for directing the rods as they are swung downwardly and rearwardly by the weight of the shock when these rods are released from their upper limit of movement.

20. 8. In a device of the class described, a frame, a binder connected with the frame, a shocker, means connected with the shocker for throwing its operative parts out of or into operation as the binder is operated, pivotally-mounted shock-supporting rods mounted on the frame outside of the binder and shocker, and means for keeping binding-twine taut as it is fed to the shocker.

25. 9. In a device of the class described, a frame, a binder connected with the frame, a shocker, means connected with the shocker for throwing its operative parts out of or into operation as the binder is operated, pivotally-mounted shock-supporting rods mounted on the frame outside of the binder and shocker, means for rocking the shock-supporting rods at their upper limit of movement and for releasing said rods to allow them to swing to their lower limit of movement, and means for feeding binding-twine to the binder and shocker and keeping said twine taut as it is being fed.

30. 10. In a device of the class described, a frame, a binder connected with the frame, a shocker, means connected with the shocker for throwing its operative parts out of or into operation as the binder is operated, pivotally-mounted shock-supporting rods mounted on the frame outside of the binder and shocker, means for directing the rods as they are swung downwardly and rearwardly by the weight of the shock when these rods are released from their upper limit of movement, and means for keeping said twine taut as it is being fed.

35. 11. In a device of the class described, a binder - needle, a shocker - needle, a knotter for the shocker-needle, means for holding the knotter out of operation during a certain number of operations of the binder and shocker needles and for operating the knotter after a certain number of operations of the needles.
